UNITED STATES PATENT OFFICE.

HANS ROSENTHAL, OF BERLIN, GERMANY, ASSIGNOR TO JULIUS PINTSCH AKTIEN-
GESELLSCHAFT, OF BERLIN, GERMANY.

GUARD FOR INVERTED INCANDESCENT MANTLES.

1,117,521.

Specification of Letters Patent. Patented Nov. 17, 1914.

Application filed July 15, 1913. Serial No. 779,177.

To all whom it may concern:

Be it known that I, HANS ROSENTHAL, a citizen of the German Empire, and residing at Berlin, German Empire, have invented 5 a certain new and useful Guard for Inverted Incandescent Mantles, of which the following is a description.

The present invention relates to means for providing a provisional or emergency 10 light in connection with incandescent gas lamps, in case the main light or flame becomes inoperative.

The invention relates more particularly to inverted incandescent gas lighting devices. 15

In view of the decreasing size of the external dimensions of a burner for a certain predetermined radiation of light, *i. e.* owing to the introduction of stronger light-units, 20 and to the employment of heating media of higher temperature, due to the employment of better gas, such as gas under pressure or previous mixture of gas and air, it has become necessary to shape the lower end of 25 the guard so as to prevent the glass from breaking, in case the mantle broke and the flame exercised its full heating power. For this purpose, among other known means, a baffle plate has been employed.

30 The object of the present invention is to provide a special incandescent body in the bottom of the guard, which shall be rendered incandescent by the heating flame when the mantle is inoperative. The same

35 result may be attained also by properly constructing the baffle plate. This body must consist of a refractory material such, for instance, as magnesium, aluminum, metal, metallic oxid or of a rare earth and may be 40 of any desired shape. In many cases this body will be advantageously made conical or provided with conical projections, in order to retain parts of the destroyed mantle or hood. The body may also be constructed as a saucer or hollow ball or cylinder, 45 with advantage, especially if holes are provided in the saucer or ball for the outlet of gases of combustion, or if they contain a material of high illuminating power, such

50 as incandescent material.

In the drawing, Figure 1 is a sectional view of a mantle carrier and guard. Figs. 2, 3, 4 and 5 show various forms of my invention adapted to be applied within the 55 supporting guard of the gas lamp.

In the drawing Fig. 1 shows any ordinary form of mantle support for a gas lamp at A, and the mantle at B with a protecting guard or frame C, this guard terminating in a base section *a*. In case the mantle is broken or 60 destroyed it is desired to continue the light in some measure and to this end I provide a separate body of incandescent material supported by the guard, preferably by the base section thereof so as to be in line with 65 the gas jet and to be made incandescent thereby. I may, as shown in Fig. 2, make this body in the form of a cup which may receive the broken parts of the mantle. Or, as shown in Fig. 3, it may be made with a 70 base of disk form and an upstanding pointed section. In Fig. 4 I have shown a pronged device, and as shown in Fig. 5 I may vary this by a series of prongs of unequal length. The flame from the gas impinging upon this body makes it incandescent, and thus when the mantle becomes defective or inoperative for any reason the incandescent body becomes effective. It is 75 also advantageous to prevent this emergency arrangement from deviating too much heat to the guard, since this would of course diminish the illuminating effect. A further improvement is attained if an automatic igniting device by means of platinum, 80 platinum black or the like material is applied to the emergency device, which would avoid the escape of unburnt gas in any case. On the other hand all devices are objectionable which glow, when the main light operates properly, as also all devices attached to the lamp glass independently of the mantle, 85 because they render the cleaning of the glass difficult, they are easily damaged and their replacement is often overlooked. The 90 guard or protecting cage is the best place for the emergency illumination.

I claim as my invention:—

1. In combination with an inverted incandescent burner having a guard, a separate incandescent body in the bottom of the guard adapted to be rendered incandescent by the main flame. 100

2. In combination with an inverted incandescent burner having a guard, a separate incandescent body in the bottom of the guard adapted to be rendered incandescent by the main flame and provided with radially extending arms. 105

3. In combination with an inverted in- 110

candescent burner having a guard, a separate incandescent body in the bottom of the guard adapted to be rendered incandescent by the main flame and having a cup 5 mounted in the bottom of the guard to receive broken parts of a defective incandescent body.

In testimony whereof I affix my signature in the presence of two witnesses.

HANS ROSENTHAL.
